OPEN MESH TEXTILE FABRIC OR SIMILAR ARTICLE

Max Sadinoff, New York, N. Y.

Application June 28, 1956, Serial No. 42,067

Term of patent 3½ years

(Cl. D92—1)

The figure is a plan view of an open mesh textile fabric or similar article embodying my new design.

The design unit shown within the broken lines in the drawing is repeated regularly along the length and width of the fabric.

I claim:

The ornamental design for an open mesh textile fabric or similar article, substantially as shown and described.
